UNITED STATES PATENT OFFICE.

THOMAS J. LITTLE, JR., OF PHILADELPHIA, PENNSYLVANIA, ASSIGNOR TO WELSBACH LIGHT COMPANY, OF GLOUCESTER CITY, NEW JERSEY, A CORPORATION OF NEW JERSEY.

ATMOSPHERIC GAS-BURNER.

No. 901,934.

Specification of Letters Patent.

Patented Oct. 20, 1908.

Application filed August 30, 1905. Serial No. 276,349.

To all whom it may concern:

Be it known that I, THOMAS J. LITTLE, Jr., of Philadelphia, in the county of Philadelphia and State of Pennsylvania, have invented a new and useful Improvement in Atmospheric Gas-Burners, of which the following is a full, clear, and exact description, reference being had to the accompanying drawings, forming part of this specification,

10 in which—

Figure 1 is a side elevation partly in section illustrating an atmospheric burner embodying one form of my invention; Fig. 2 is a partial sectional view of the same, showing the parts in a different position; Fig. 3 is a sectional view of the modified form; Fig. 4 is an enlarged detail view showing a part of Fig. 5; Fig. 5 is a sectional view showing another modification of the invention; and Fig. 6 is a sectional elevation showing the burner in place.

In the operation of atmospheric gas burners employed with incandescent mantles, in which the gas previously to its ignition is mixed with a supply of air, difficulty has been experienced because the conditions which exist when the burner is first ignited differ from those existing after the burner has become heated. Special difficulties are 30 also met in using such burners in an inverted position, since the air will flow down a burner tube much more sluggishly when the tube is hot than when it is cold, and the effect of the heat is to diminish the relative 35 proportion of air. Therefore, if the burner inlets are so proportioned as to admit a proper supply of air for the initial lighting, the proportion of air in the mixture will become too small after the burner has been 40 lighted; and if they be constructed to deliver a proper proportion of air for the normal operation of the burner, the supply of air at the lighting period will be unduly large, and the burner will flash back when 45 ignited, or it may even be impossible to ignite the burner except by repeated applications of a flame.

My invention overcomes these and other difficulties and provides for automatically 50 reducing the relative proportion of air at the time of ignition, thereby avoiding flashbacks; while the relative amount of air is increased during the normal action of the burner, so as to provide the proper amount 55 of air at such time.

It consists of a thermostatic device having at least a portion thereof in the feed channel for the mixture of air and gas, and preferably in the form of an impedance, the thermostatic device being arranged to reduce the relative amount of air during ignition and to increase the relative amount of air in the mixture during normal operation when the parts are heated.

The invention is especially valuable for 65 the inverted types of burners using incandescent mantles.

In the several figures of the drawings, A is an inverted atmospheric burner, which is provided with a thermostatic impedance device, operating to throttle or restrict the flow of air in the initial operation of the burner.

In Figs. 1 and 2, which show my preferred form, b represents a cone constructed 75 of thermostatic material and split through its apex. This cone is placed in the burner tube between the burner tip and the air supply inlet or inlets, and when cold it assumes a conical form with the slits of 80 comparatively small size, as shown in Fig. 1. When the burner is cold it constitutes an impedance to the burner feed and operates to prevent flash-back in two ways: first, by throttling the burner feed and reducing the relative amount of air in the mixture; and second, by preventing the flame passing back, owing to its foraminous character. As the burner gradually heats up after lighting, the part b, by reason 85 of its thermostatic character, automatically opens, substantially as shown in Fig. 2, and then substantially ceases to obstruct the burner feed. The proportion of air is thus increased to the desired amount and the mixture may burn in the ordinary way.

In Figs. 3 and 4, the thermostatic impedance comprises a deflector c, carried by a thermostatic arm d, secured as by means of a thimble c', within the atmospheric burner 100 tube. When the burner is cold the deflector occupies the position shown in Fig. 3, in which it obstructs the jet of gas issuing from the jet orifice f, and thus limits the amount of air drawn into the burner. After the burner 105 becomes heated, the thermostatic arm d shifts the deflector or baffle c, toward the inner wall of the burner and thus stops or reduces its action on the burner feed.

In the form of Fig. 5, the thermostatic 110

arm *g* operates upon the movable member *h* of the air shutter, serving to reduce the area of air inlet when the burner is cold and enlarge the air inlet area when the burner is warm, thus controlling the entering air and reducing its proportion at the time of ignition.

In Fig. 6, *i* represents the glass globe, *j* the holding means for the same, and *x* the mantle.

The advantages of my invention result from preventing flash-backs at the time of lighting by reducing the proportion of air in the mixture, while at the same time affording the proper proportions of air and gas during the normal operation. In the preferred form, the impedance character of the thermostat also aids in avoiding flash-backs during lighting, it then being shifted or removed to avoid clogging or carbonizing. The opening and closing movements of the prongs in this form clears them of any material collecting thereon.

By the words "in the channel for the mixture feed" in the claims I do not intend to restrict myself to placing the thermostatic device or thermostatically controlled impedance entirely within this tube; but to recite that operating parts thereof are in said channel.

Many variations may be made in the form and arrangement of the thermostat and its position without departing from my invention.

35 I claim:

1. An atmospheric gas burner having a thermostatic device located in the channel for the mixture feed, said device being arranged to reduce the proportion of air at the

time of ignition and to increase the proportion of air under the influence of heat for the normal operation of the burner; substantially as described.

2. An atmospheric gas burner having a thermostatically controlled impedance in the channel for the mixture feed arranged to prevent flash-backs at the time of ignition, the impedance being shifted by the action of heat for the normal operation of the burner, substantially as described.

3. An atmospheric gas burner having a thermostatic impedance in the channel for the mixture feed, said impedance being arranged to allow a flow of the mixture at all times, substantially as described.

4. An atmospheric gas burner of the inverted type having a thermostatically-controlled impedance in the channel for the mixture feed, said impedance being arranged to allow a flow of the mixture at all times, substantially as described.

5. An atmospheric gas burner having in its burner tube a thermostatic device consisting of a split cone, substantially as described.

6. An atmospheric gas burner of the inverted type having in its burner tube a thermostatic device consisting of a tubular member having a series of inwardly projecting prongs arranged to spread under the action of heat, substantially as described.

In testimony whereof I have hereunto signed my name.

THOMAS J. LITTLE, JR.
